ABSTRACT OF THE DISCLOSURE

A through-the-roof flue and air intake assembly for sealed combustion heaters having concentric air intake and flue exhaust pipes, the flue pipe terminating above the air intake pipe and both pipes being provided with outwardly-extending caps. The improvement comprises providing an outwardly-exposed section of the flue pipe between the caps where the exposed section has a vertical height of from .5 to 2, or preferably .6 to .9, times its outside diameter. The upper portion of the flue pipe which provides the exposed section can have a larger internal diameter than the portion below the lower cap, the upper portion of the flue pipe preferably providing from 25 to 75% more cross-sectional area than the lower portion thereof.

This invention relates to a through-the-roof flue and air intake assembly. Devices like the assembly of the present invention are sometimes referred to as "roof jacks." They are particularly adapted for use with sealed combustion heaters. The roof jack of this invention may be advantageously employed with the sealed combustion wall heater described in co-pending application Ser. No. 576,884, filed Sept. 2, 1966, now Patent No. 3,361,125, entitled "Sealed Combustion Wall Heater."

Roof jacks for sealed combustion heaters are known devices which have been widely employed in the United States. Representative devices of this kind are described in Patents 2,634,720; 2,818,060; 2,754,816; and 2,942,600. The roof jack of the present invention is designed as an improvement on such prior art constructions.

In the designing of roof jacks for sealed combustion heaters, it has been recognized that the fresh air intake and the flue gas exhaust should be located in substantially the same pressure zone. This has led to the construction of the roof jacks with the fresh air inlet and the flue gas outlet as close together as possible. In the development of the present invention, it was discovered that a wider vertical spacing between the intake and exhaust positions provides certain important advantages. These advantages relate particularly to the minimizing of wind effects. With prior constructions under some wind conditions, a positive pressure can be developed in the area between the exhaust and intake caps, and this can reduce or even reverse the desired flows of flue gas and combustion air. While it is desired to maintain a lower pressure adjacent the flue gas exhaust than adjacent the fresh air intake, it is not necessarily desirable to discharge the flue gases at maximum velocity. Since the rising flue gases strike the inside of the cap covering the top of the flue pipe, the higher the velocity, the greater the back pressure developed by the reversal of flow direction in discharging the flue gases through the open bottom of the cap.

It is therefore a general object of the present invention to provide an improved through-the-roof vent and air intake assembly which substantially overcomes the problems and difficulties described above. More specifically, it is an object to provide a roof jack of the character

2

described which minimizes wind velocity effects adjacent the flue gas exhaust, and which substantially precludes development of a higher pressure in this area than the pressure adjacent the combustion air intake, although both the exhaust and intake are in substantially the same pressure zone. A related object is to provide means for reducing the back pressure caused by reversal of flow of the flue gases adjacent the top of the flue pipe. Further objects, advantages, and results will be indicated in the following specification.

This invention is shown in an illustrative embodiment in the accompanying drawing, in which—

FIGURE 1 is a side elevational view of a through-the-roof flue and air intake assembly embodying the features of the present invention;

FIG. 2 is a side elevational sectional view showing the internal construction of the assembly of FIG. 1; and

FIG. 3 is a top view of the assembly with portions broken away to show the means for attaching or supporting certain of the components.

The roof jack or flue and air intake assembly, as illustrated in FIGS. 1-3, may be fabricated primarily from sheet metal, such as aluminum or galvanized steel. It consists essentially of a series of concentric tubes or sleeves, which are formed or arranged in a particular manner, and which provide combustion air intake and flue gas exhaust passages, and also includes annular flue exhausts and air intake ports which are covered by suitable caps. The roof jack is adapted for installation on the roof of a dwelling unit, such as a mobile home, where the room immediately below the roof jack is being heated by a wall-type furnace having a sealed combustion construction. A furnace of this type is described in co-pending application Ser. No. 576,884, filed Sept. 2, 1966, entitled "Sealed Combustion Wall Heater."

Turning now to a detailed description of the invention, and looking first at FIG. 1, the assembly can be seen to include an upper or first cap 10 which is mounted by brackets 11 on a tubular member 12, and a lower or second cap 13 which is mounted on a tubular member 14 by brackets 15. The assembly also includes a horizontally-extending plate 16, which is adapted for mounting on the top of the roof, and a shield or spacer sleeve 17 which is adapted to extend below plate 16 within the roof. The inventive features are more particularly illustrated in FIG. 2, which will now be discussed in detail.

Starting from the innermost of the tubular members, the assembly includes vertically-extending flue pipe means designated generally by the number 18. In the illustration given, the flue pipe means is formed from tube 19 and the upper portion 20 of tube 21, and it has its lower portion concentrically enclosing tube 19. The upper tubular portion 20 which forms an extension of flue tube 19 is enclosed on the outside by the tube or sleeve 12 so that tube 12 in effect provides a cylindrical outer surface for the upper portion of the flue pipe means 18. As indicated in FIG. 2 and shown more clearly in FIG. 3, the upper end of tube 20 provides tabs 21 which are folded downwardly over the upper end of tube 12 to hold it in place. The lower end of tube 12 is provided with a rolled edge 12a. The upper end of the flue pipe means 18, as provided by the composite of tube section 20 and tube 12, is open for the discharge of flue gas as indicated at 22.

As indicated in FIG. 1 and shown more clearly in FIG. 2, the first or upper cap 10 is of concavo-convex configuration and is arranged to extend horizontally over the open upper end 22 of the flue pipe means 18, the underside of the cap providing the concave surface against which the flue gases are discharged from the top of the flue pipe. Cap 10 is supported in upwardly-spaced relation to opening 22 and the upper end of flue pipe means 18 so that

flue gases can exit between the upper end of pipe means 18 and the inside of cap 10, the desired exit flow being indicated by the arrows in FIG. 2. Preferably, the lower edge 10a of cap 10 is positioned at a level substantially the same as the upper end of the flue means 18. In the illustration given, edge 10a extends slightly below the upper ends of tube 12 and tube section 20. The lower portion of cap 10 has a diameter appreciably greater than the outside of sleeve 12 to provide a relatively wide annular space 23 for the discharge of the flue gases.

Cap 10 may be supported in any suitable manner. In the illustration given, four of the support brackets 11 are provided at 90° spacings around tube 12. The triangular shaped brackets 11 include an inner right angle flange 11a, as shown in FIGS. 1 and 3, which may be spot welded to the outside of tube 12, and also an outer right angle flange 11b, as shown in FIG. 3, which may be spot welded to the inside of the lower portion of cap 10, thereby firmly supporting cap 10 on tube 12.

The assembly also includes air intake pipe means designated generally by the number 24. Air intake pipe means 24 is of larger diameter than flue pipe means 18 and is arranged to concentrically enclose the lower portion of the flue pipe means, extending around tube 19 for most of its length. In the illustration given, pipe means 24 is formed from a lower tube section 25 and an upper tube section 14. The upper end of pipe means 24 as provided by tube section 14 terminates at a distance below the top of flue pipe means 18, and provides an annular opening 26 for the intake of air.

Air intake opening 26 is covered by the second or lower cap 13, as shown more clearly in FIG. 2. Cap 13 is also of concavo-convex configuration, the inner convex surface facing downwardly towards opening 26, and the cap extending horizontally outwardly beyond the sides of tube 14 to provide an annular intake opening 27. Cap 13 has a central opening 28 which receives the adjacent portion of the flue pipe means 18 comprising the tube section 20 of tube 21. Cap 10 is supported in upwardly spaced relation with respect to the top of air intake pipe means 24 and opening 26. This permits the air to enter as indicated by the arrow in FIG. 2.

Cap 13 is supported by brackets 15 which are similar in construction and arrangement to brackets 11 which support cap 10. Brackets 15 include an inner right angle flange portion 15a which is spot welded to tube 14 and an outer right angle flange portion 15b which is spot welded to the inside of the lower portion of cap 13, as shown more clearly in FIG. 3. Thus, cap 13 is securely supported on tube 14.

Preferably, as shown, caps 10 and 13 are of substantially identical size and configuration. It is particularly desirable that their lower portions have substantially the same diameter. However, in certain embodiments of the present invention, caps 10 and 13 may be of different sizes, such as constructions wherein cap 13 has a greater diameter than cap 10.

The roof jack of the present invention is particularly characterized by the relation of the distances y and x as indicated by the dimension lines in FIG. 2. The dimension x is the vertical distance between the lower edge 10a of cap 10 and the top or uppermost surface portion of cap 13, which is the portion of the cap immediately adjacent the central opening 28. It will be understood, of course, that the upper surface of cap 13 curves downwardly from the central portion around opening 28. The distance y represents the external diameter (O.D.) of the upper end portion of flue pipe means 18 which extends between the caps 10 and 13. In the illustration given, the outer surface of the flue pipe means at this point is provided by the outside of tube 12, and therefore the distance y is the O.D. of tube 12. In accordance with the present invention, the vertical distance x should equal from .5 to 2 times the diameter y . In preferred embodiments, the distance x equals from .6 to .9 times the diameter y . For

example, the O.D. of tube 12 may be approximately 3.2 inches while the vertical distance x is approximately 2.5 inches. With these specific dimensions, the caps 10 and 13 may have lower portion diameters of about 6.75 inches. The overall height of the assembly from plate 14 to the top of cap 10 can be about 9 inches, while the clearance between the lower edge of cap 13 and plate 14 can be about 3 inches.

Also, in accordance with the present invention, the upper portion of flue pipe means 18 may have a larger internal diameter than the lower portion. For example, tube 19 has a substantially smaller internal diameter than tube section 21 which forms the upper portion of the flue means. The transition between the diameter of pipe 19 and the diameter of pipe section 20 is provided by the enlarged connecting portion 19a, which can be united to tube 21 immediately below its section 20 by spot or arc welding. Preferably, the connection at this point provides substantially a hermetic seal so that the annular space 29 between tubes 19 and 21 is essentially a dead air space with no communication with the flue outlet.

In the preferred embodiment, as shown, the enlarged upper portion of the flue pipe means 18 begins at about the top of cap 13 and extends thereabove to the flue outlet 22. However, the principal requirement is that the upper portion of the flue pipe means has an increased internal diameter as compared with the lower portion. The upper portion of the flue pipe therefore provides a greater cross sectional area as compared with the lower portion, thereby reducing the velocity of the flue gases before they impinge on the underside of cap 10.

In a specific preferred embodiment, the internal diameter of tube 19 can be approximately 2.5 inches, while the internal diameter of tube section 20 is approximately 3.1 inches. With this construction, the upper portion of the flue outlet provides about 50% greater cross sectional area than the lower portion. In other embodiments, the cross sectional area of tube section 20 may be from 25 to 75% greater than the cross sectional area of tube section 19.

The lower portion of tube 20 which surrounds tube 19 and is separated therefrom by the annular space 29 serves as a jacket for the flue. This jacketing arrangement minimizes the transfer of heat from the flue gas to the incoming hot air by supplying cooler air to the furnace, which improves combustion capacity.

The lower ends of tubes 20 and 18 may be flared to facilitate the insertion of connecting pipes. In the inwardly formed rib 19b toward the upper portion of tube 19 serves as a stop for the upper end of the flue pipe. It will be understood that connecting pipes will also be inserted within tube 29 and around the outside of tube 25, thereby providing continuous flow passages. No tubular member will usually be connected with shield 17, since this is not designed to provide a flow passage. When the unit is installed, the plate 14 will be at the roof level, and the portions of the assembly above plate 14 will extend above the roof line.

The operation of the roof jack will be largely apparent from the foregoing description. However, the salient features may be briefly summarized as follows. The flue gases rise through the tube 19 and then expand outwardly into the increased volume of the tube section 20, which has the result of reducing the velocity of the flue gases. The flue gases of reduced velocity are directed against the inside of cap 10 and are caused to reverse their flow, being discharged through the annular outlet 23. The pressure maintained adjacent the outlet 23 will be lower than the pressure adjacent the fresh air inlet 27. This will be true even under adverse wind conditions due to the spacing provided between the caps 10 and 13, as described above.

While in the foregoing specification this invention has been described in relation to a specific embodiment thereof and many details have been set forth for purposes of

illustration, it will be apparent to those skilled in the art the invention is susceptible to other embodiments, and that certain of the details described herein can be varied without departing from the basic principles of the invention.

We claim:

1. A through-the-roof flue and air intake assembly for a sealed combustion heater, including vertically-extending flue pipe means having an upper portion with a cylindrical outer surface and an open upper end; a first horizontally-extending concavo-convex cap supported over said flue pipe means upper end, said cap terminating at a lower end having a diameter greater than said flue pipe means and said cap means being supported in spaced relation to said flue pipe means upper end so that flue gases can exit between said upper end and the inside of said cap; air intake pipe means of larger diameter than said flue pipe concentrically enclosing the lower portion thereof, said air intake pipe having an open top terminating at a distance below the top of said flue pipe means; and a second horizontally-extending concavo-convex cap providing a central opening receiving said flue pipe, said second cap being of larger diameter than said air intake pipe means and being supported in spaced relation to said air intake pipe means top so that air can enter between the inside of said second cap and the outside of said air intake pipe means top: wherein the improvement comprises having the cylindrical outer surface of the portion of said flue pipe between said first and second caps directly exposed to the outside atmosphere while being dimensioned to control wind effects, said exposed flue pipe portion between said first cap lower edge and the upper surface of the portion of said second cap around said opening having a vertical length equalling from .6 to .9 times its outside diameter, said exposed flue pipe portion internally providing a substantially sealed extension of said flue pipe with a larger internal diameter than the portion thereof below said second cap, the said enlarged upper portion of said flue pipe having from 25 to 75% more cross-sectional area than the said smaller lower portion thereof.

2. A through-the-roof flue and air intake assembly for a sealed combustion heater, including vertically-extending flue pipe means having an upper portion with a cylindrical outer surface and an open upper end; a first horizontally-extending cap supported over said flue pipe means upper end, said cap terminating at a lower end having a

diameter greater than said flue pipe means and said cap means being supported in spaced relation to said flue pipe means upper end so that flue gases can exit between said upper end and the inside of said cap; air intake pipe means of larger diameter than said flue pipe concentrically enclosing the lower portion thereof, said air intake pipe means having an open top terminating at a distance below the top of said flue pipe means; and a second horizontally-extending cap providing a central opening receiving said flue pipe means, said second cap being of larger diameter than said air intake pipe means and being supported in spaced relation to said air intake pipe means top so that air can enter between the inside of said second cap and the outside of said air intake pipe means top; the improvement characterized by the cylindrical outer surface of the portion of said flue pipe between said first and second caps directly exposed to the outside atmosphere while being dimensioned to control wind effects, said exposed flue pipe portion between said first cap lower edge and the upper surface of the portion of said second cap around said opening having a vertical length equalling from .5 to 2 times its outside diameter, and the portion of said flue pipe above said second cap providing a substantially sealed extension of said flue pipe with a larger internal diameter than the portion of said flue pipe below said second cap, the said enlarged upper portion of said flue pipe having cross-sectional area of from 25% to 75% greater than the said smaller lower portion thereof.
